UNITED STATES PATENT OFFICE

SAMUEL J. MIROSAV, OF DALLAS, TEXAS

DESIGN FOR A HOUSE NUMBER PLATE

Application filed July 8, 1929. Serial No. 31,968. Term of patent 3½ years.

To all whom it may concern:

Be it known that I, SAMUEL J. MIROSAV, a citizen of the United States, residing at Dallas, in the county of Dallas and State of Texas, have invented a new, original, and ornamental Design for House Number Plates, of which the following is a specification, reference being had to the accompanying drawing, forming part thereof.

I claim:

The ornamental design for a house number plate, as shown.

SAMUEL J. MIROSAV.
